UNITED STATES PATENT OFFICE.

CLYDE WILLIAM STUART, OF BROOKLINE, MASSACHUSETTS.

NECKTIE-HOLDER.

1,182,112.

Specification of Letters Patent.

Patented May 9, 1916.

Application filed December 6, 1915. Serial No. 65,169.

To all whom it may concern:

Be it known that I, CLYDE WILLIAM STUART, a citizen of the United States, residing at Brookline, in the county of Norfolk and 5 State of Massachusetts, have invented new and useful Improvements in Necktie-Holders, of which the following is a specification.

This invention relates to improvements in necktie holders and has for its object to provide an inexpensive device upon which a tie of the well-known four-in-hand type may be tied or untied at will, but which, when tied, upon said holder, may be quickly applied to a collar and held in place by means of a simple 10 fastening device attached to said holder and thereby eliminate the necessity of passing the tie around the collar.

Another object of the invention is to provide a holder which permits the knot of the 15 tie to be moved, if desired, to a different place each time the tie is tied upon said holder, and at the same time permit the ends of said tie to be equal in length.

Another object of the invention is to provide a holder constructed of such flexible or 20 resilient material that it may be bowed outwardly when applied to the collar, so as to cause the tie when in place to protrude slightly between the waistcoat and collar of 25 the wearer thereof.

The invention consists in the combination and arrangement of parts set forth in the 30 following specification and particularly pointed out in the claim.

Referring to the drawings: Figure 1 is a 35 front elevation of the necktie holder embodying my invention with a tie shown attached thereto, said necktie and holder being shown attached to a collar. Fig. 2 is a section taken substantially on the line 2—2 of 40 Fig. 1. Fig. 3 is a detail front view of the holder. Fig. 4 is a detail side elevation of the same. Fig. 5 is a detail view of another form of fastening device for the necktie 45 holder.

Like numerals refer to like parts throughout the several views of the drawings.

In the drawings, 5 is a holder which is 50 preferably T-shaped, that is to say, it comprises a transverse member 6 arranged at the top thereof with the extremities 7 and 8 of said transverse member deflected upwardly. A vertically disposed member 9 depends 55 from the transverse member 6 extending for a substantial distance therebelow, and this member has at its lower end a fastening

means 10, in the present instance a safety pin, which is adapted to pass through perforations 11 formed adjacent to said lower end.

The T-shaped member 5 is preferably 60 formed of some flexible or resilient material such as whalebone or celluloid, preferably the latter. The vertically disposed member 9 of said holder is preferably bowed outwardly intermediate of the lower and upper 65 ends thereof as at 12, so as to cause the tie which is attached thereto to protrude outwardly between the vest which is illustrated in Fig. 1 at 13 and the collar 14.

The vertically disposed member of the 70 holder is made sufficiently long to extend below the upper edge of the waistcoat 13 and at this point said vertically disposed member is secured by the fastening device or pin 11 to the front of the shirt of the wearer. 75 The extremities 7 and 8 are adapted to extend outwardly between the folds of a turned-down collar as illustrated in Fig. 1. In tying the necktie upon the holder 5 said tie is first doubled substantially at the middle 80 thereof, so as to bring the extremities 15 and 16 together. The folded end of the tie as illustrated at 17 is then laid against the front face of the holder 5, a substantial distance below the juncture of the vertically 85 disposed member 9 with that of the transverse member 6. The two folds of said tie then extend upwardly over the upper edge of said transverse member 6, thence downwardly against the rear face thereof and 90 around the front as at 18, lying against the doubled end of said tie. From thence the tie is passed around the rear of the transverse member 6, upwardly over the first course and then downwardly between the 95 portion 18 and the doubled end 17 as at 19, thus forming the knot 20. The tie holder 5 is perforated at 21 adjacent to the juncture of the vertically disposed member 9 and the transverse member 6 to receive a fastening 100 device preferably a pin 22 which is passed through said perforations and into the rear portion of the knot of said tie, thus firmly securing said tie to the holder temporarily.

In applying the tie with its holder to the 105 collar the extremities 7 and 8 thereof are inserted between the folds thereof and pushed upwardly as far as the knot of said tie permits it to go. The lower extremity 23 at which the fastening means 10 is located 110 is then pressed upwardly sufficient to cause the bulged portion 12 to protrude a sufficient

distance between the upper portions of the waistcoat 13 and said collar after which said vertically disposed member 9 is secured in place by the fastening means 10 to the front of the shirt. There is sufficient resiliency in the material from which the holder is constructed to maintain the extremities 7 and 8 of the transverse member 6 in position beneath the collar when the lower extremity 10 of the vertically disposed member has been secured in place by the fastening device 10.

To remove the tie from the collar, all that is necessary is to detach the lower end of the holder from the shirt front and withdraw the transverse member 6 from the collar.

Referring now to Fig. 5, 9' represents the lower end of the vertically disposed member and to said vertically disposed member I have attached a well-known type of tie clasp 24 which may be employed in place of the safety-pin illustrated in the preceding figures.

Having thus specifically described my in-

vention what I claim and desire by Letters Patent to secure is:

A necktie holder constructed of resilient material and comprising a transverse member adapted to extend between the folds of a turn-down collar, a vertically disposed member connected with said transverse member substantially midway thereof, said holder free from connection with the usual front collar button, and fastening means at the lower end of said vertically disposed member adapted for attachment to the shirt at a substantial distance below the neckband of said shirt, whereby the transverse member is yieldingly retained in position between the folds of said collar.

In testimony whereof I have hereunto set my hand in presence of two subscribing witnesses.

CLYDE WILLIAM STUART.

Witnesses:

SYDNEY E. TAFT,
H. R. STUART.
